UNITED STATES PATENT OFFICE.

GUSTAV LEIST, OF NEW YORK, N. Y.

CIGAR-BUNDLING MACHINE.

SPECIFICATION forming part of Letters Patent No. 365,926, dated July 5, 1887.

Application filed November 17, 1886. Serial No. 219,143. (No model.)

To all whom it may concern:

Be it known that I, GUSTAV LEIST, of the city, county, and State of New York, have invented certain new and useful Improvements 5 in Cigar-Bundling Machines or Blocks, of which the following is a specification.

My invention is designed to furnish an improved bundling-block for cigar-packers, by which any size and number of cigars can be packed into bundles of any required size, so that one and the same block can be used for the different work for which such a block is used in practice; and the invention consists of a cigar-bundling block composed of a base-piece having longitudinal guide-slots, inclined horns made adjustable on said base-piece, and a laterally-adjustable back having fixed rods guided in eyes of the base-board, an adjusting-screw applied to the back and engaging a threaded sleeve applied to the base-board.

In the accompanying drawings, Figure 1 represents a perspective view of my improved cigar-bundling block. Fig. 2 is a bottom view 25 of the same drawn on a larger scale; and Fig. 3 is a vertical transverse section on line *xx*, Fig. 2.

Similar letters of reference indicate corresponding parts.

A in the drawings represents a base-board, and B the rear wall or back of my improved cigar-bundling block. The base-board A is provided with longitudinal slots or ways *aa*, and with inclined horns C C, which are guided 30 in said ways by means of shanks *a'*, of smaller thickness than the body of the horns. The shanks *a' a'* are connected below the base-board A by a transverse piece, C', that is clamped to the under side of the base-board A. 35 by means of clamping-screws *b b*, as shown clearly in Figs. 2 and 3. The inclined horns C C may be adjusted to any distance from each other on the base-board A, according to the size of the bundles to be made. For bundling 40 small cigars into small bundles the horns are set closer to each other, while for bundling large cigars or large sizes of bundles they are moved farther away from each other. The back B is guided by horizontal rods *d d*, that

are attached at their ends rigidly to the back 50 B, and are guided in eyes *d'* of the base-board A, and the back is adjusted nearer to or farther from the base-board A by a center-screw, D, that turns in a retaining-plate of the back B, and engages at its inner end an interiorly-threaded sleeve, D', attached to the underside of the base-board A. To produce the uniform adjustment at both ends of the back from the base-board, spiral springs *e* are placed on the rods *d d*, between the back B and the rear 60 guide-rings, *d'*, as shown in Fig. 2. The adjustable back B forms a gage, which can be adjusted to cigars of different length, so that the fastening-ribbon can be placed centrally around the cigar-bodies and tied at the proper 65 position on the bundle.

The bundling-block is used in the same manner as the ordinary bundling-block heretofore in use, with the exception that the horns and back are first adjusted to the size of the 70 bundles and length of the cigars to be bundled. After they have been adjusted the ribbon is placed on the base-board longitudinally between the two pairs of horns, close to the front-horns. The required number of cigars— 75 say from fifty to one hundred—is then placed between the inclined faces of the horns and the ribbon then tied tightly around the bundle. When another size of cigar is to be bundled, the back and horns are readjusted 80 again and the same process of bundling repeated. The cigars are bundled uniformly, as the ribbons are located in all the bundles of a certain size at the same point relatively to the length of the cigars, so as to produce a 85 uniform and neat appearance when packed in the boxes.

I am aware that cigar-bundling blocks in which adjustable horns are guided on a base-board and adjusted to different distances from 90 each other have been used heretofore. I am also aware that a cigar-bundling block provided with a laterally-adjustable back has been used heretofore, and I do not claim these features, broadly.

Having thus described my invention, I claim 95 as new and desire to secure by Letters Patent—

The combination, with a base-board having

longitudinal ways, of adjustable horns guided in said ways, clamps for attaching the horns to the base-board, a laterally - adjustable back having fixed rods guided in the eyes of the 5 base-board, an adjusting-screw applied to the back, and a threaded sleeve applied to the base-board, substantially as set forth.

In testimony that I claim the foregoing as my invention I have signed my name in the presence of two subscribing witnesses.

GUSTAV LEIST.
